ATT'Y.

UNITED STATES PATENT OFFICE.

JOHN E. LEAVITT, OF MELROSE, MASSACHUSETTS, ASSIGNOR TO HELEN I. YOUNG, OF BOSTON, MASSACHUSETTS.

POLISHING APPARATUS.

SPECIFICATION forming part of Letters Patent No. 593,302, dated November 9, 1897.

Application filed November 7, 1896. Serial No. 611,315. (No model.)

To all whom it may concern:

Be it known that I, JOHN E. LEAVITT, of Melrose, county of Middlesex, and State of Massachusetts, have invented an Improvement in Polishing Apparatus for Stoves, of which the following description, in connection with the accompanying drawings, is a specification, like letters on the drawings representing like parts.

- 10 This invention relates to a device or apparatus for polishing articles, and especially stoves, and has for its object to provide a simple and efficient apparatus with which liquid blacking may be applied to the stove in desired quantities and the stove then polished without soiling the hands of the operator and without spattering the liquid blacking on the walls, woodwork, or floor of the kitchen or other room.
- 15 In accordance with this invention the apparatus consists, essentially, of a receptacle for the liquid blacking provided with an outlet port or opening which is controlled by a valve, as will be described, and a polishing-surface, preferably of lambs' wool, felt, or other soft or similar absorbing material, which is secured to the bottom of the receptacle and is designed to effect the polishing of the stove with the liquid blacking supplied thereon.
- 20 25 30 35 40 45 50 55 60 65 70 75 80 85 90 95 100
- from the receptacle. These and other features of this invention will be pointed out in the claim at the end of this specification.

Figure 1 is a side elevation of an apparatus embodying this invention; Fig. 2, a top or plan view of the apparatus shown in Fig. 1, and Fig. 3 a vertical section of the apparatus to be referred to.

Referring to the drawings, A represents a receptacle or box for the liquid blacking, the said receptacle being shown in the present instance as composed of a top a, bottom a', and annular rim or side a². The bottom a' is preferably provided with a depending flange a³ and is secured liquid-tight to the side a² by solder a⁴.

45 The receptacle or box A is mounted upon a base b of suitable material, preferably wood, and the said base is preferably made square or angular and is provided with a raised central portion b', over which the flange a³ of the bottom are fitted, and to which the side a² and

flange a³ are secured by tacks, nails, or other suitable devices b². The base b has secured to it a polishing-surface b³, preferably lambs' wool, but which may of felt, cloth, or other suitable material capable of absorbing the liquid blacking. The polishing-surface b³ is secured to the base in any suitable manner and is represented as covering the bottom and overlapping the upper sides of the same, so that the edges of the base are covered with polishing material which enables the corners, cracks, and ornamental designs to be polished as well as plain surfaces.

The liquid-receptacle A is provided with an inlet-opening, normally closed by a cap b⁴, and the said liquid-receptacle is provided, as herein shown, with a discharge port or opening b⁵, made in a centrally-disposed pipe or tube b⁶, (see Fig. 3,) which is extended from the top of the receptacle A through the base b, and the polishing-surface b³ is provided with an opening b⁷ in line with the tube or pipe b⁶, so that the liquid flowing from the receptacle through the tube or pipe b⁶ may pass directly onto the stove.

The tube or pipe b⁶ has inserted into it a tube or pipe b⁸, having an opening or port b⁹, which is adapted to register with the opening or port b⁵ for the passage of the liquid from the receptacle A through the said ports into the tube b⁸ and thence through the tube b⁶ and hole b⁷ in the polishing-surface. The tube b⁸ constitutes a rotary valve by which the port b⁵ may be opened and closed, and the tube b⁸ is extended up through the top or cover a and has secured to it a finger-piece or handle b¹⁰, by which the valve may be turned from the position represented by full lines in Fig. 2 to that represented by dotted lines in said figure, the dotted-line position representing the valve b⁸ as opened.

The top or cover a may be provided with a projection b¹², constituting a stop to limit the rotary movement of the finger-piece b¹⁰, thereby insuring the valve being maintained open.

The receptacle A may have secured to its side a² a handle b¹⁵, which may be of metal, as herein represented, but which will preferably be provided with a non-heat conducting covering, such as wood.

The receptacle A is rendered liquid-tight around the tube b⁸ by solder b²⁰. (See Fig. 3.)

In the operation of my improved polishing apparatus the receptacle A is filled with liquid blacking by removing the cap b⁴, the valve b⁸ being at such time closed. When the receptacle A has been filled, the cap b⁴ is replaced, and if it is desired to use the apparatus it is placed over the stove and the valve 5 opened by turning the finger-piece b¹⁰ from the full-line position shown in Fig. 2 to that indicated by dotted lines. The liquid then flows through the ports b⁵ b⁹ onto the stove, and after a sufficient or desired quantity of 10 the liquid blacking has been discharged onto the stove the finger-piece b¹⁰ is moved onto the full-line position and the valve b⁸ closed. The operator then moves the polishing-surface over the stove after the manner now commonly practiced with blacking-brushes, and 15 the lambs' wool or other absorbing material absorbs the surplus liquid, while at the same time it polishes the stove. After a few operations the polishing-surface becomes saturated with the liquid blacking, so that in subsequent operations but a small quantity of 20 liquid blacking is required to polish the stove.

I have herein represented one construction

and form of apparatus; but I do not desire to limit my invention to the particular form and 30 construction shown.

I claim—

In a polishing apparatus for stoves and like articles, the combination of the following instrumentalities, viz: a liquid-receptacle A 35 provided with an inlet and with an outlet and with a depending flange a³, a base upon which the said receptacle is mounted having a raised portion b' over which the flange a³ is fitted, the said raised portion having an outlet-passage adapted to communicate with the interior of the said receptacle, means to fasten the flange a³ to the said raised portion of the base, a polishing-surface of lambs' wool 40 secured to the said base, and overlapping the upper sides of the same to cover the edges of the said base, and a valve coöperating with the outlet-port for the liquid-receptacle, substantially as described.

In testimony whereof I have signed my 50 name to this specification in the presence of two subscribing witnesses.

JOHN E. LEAVITT.
